US0D1019929S

(12) **United States Design Patent** (10) **Patent No.:** **US D1,019,929 S**
(45) **Date of Patent:** **** Mar. 26, 2024**

(54) **SET OF NOISE REDUCTION EARPLUGS**

(71) Applicant: **SHENZHEN XIANGYUE TENGDA TECHNOLOGY CO., LTD.**, Shenzhen (CN)

(72) Inventor: **Yitong Lin**, Shenzhen (CN)

(73) Assignee: **SHENZHEN XIANGYUE TENGDA TECHNOLOGY CO., LTD.**, Shenzhen (CN)

(**) Term: **15 Years**

(21) Appl. No.: **29/820,845**

(22) Filed: **Dec. 23, 2021**

(51) LOC (14) Cl. **24-01**

(52) U.S. Cl.

USPC **D24/106**

(58) **Field of Classification Search**

USPC D24/106, 173, 174, 175; D14/223;

D29/112

CPC A61F 11/08; A61F 11/12; A61F 11/085;

H04R 1/1016

(57) **CLAIM**

The ornamental design for set of noise reduction earplugs, as shown and described.

DESCRIPTION

FIG. 1 is a perspective view of set of noise reduction earplugs showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
